United States Patent Office

Des. 187,352
Patented Mar. 1, 1960

187,352

AIRCRAFT

Murray Dryer, Berea, John R. Jack, North Olmsted, and Roger W. Luidens, and Nicholas E. Samanich, Cleveland, Ohio, assignors to the United States of America as represented by the Secretary of the Navy

Application September 25, 1957, Serial No. 47,871

Term of patent 14 years

(Cl. D71—1)

(Granted under Title 35, U.S. Code (1952), sec. 266)

Fig. 1

Fig. 2

Fig. 3

Figure 1 is a perspective view of an aircraft showing our new design;

Figure 2 is a side elevational view thereof; and

Figure 3 is a bottom perspective view thereof.

The invention described herein may be manufactured and used by or for the Government of the United States

of America for governmental purposes without the payment of any royalties thereon or therefor.

We claim:

The ornamental design for an aircraft, as shown.
